UNITED STATES PATENT OFFICE.

JOHN McGRANIGHAN, OF ROXBORO, PENNSYLVANIA.

RAILWAY-TIE.

No. 894,525.

Specification of Letters Patent.

Patented July 28, 1908.

Application filed December 5, 1907. Serial No. 405,189.

To all whom it may concern:

Be it known that I, JOHN McGRANIGHAN, a citizen of the United States, residing at Roxboro, in the county of Philadelphia and 5 State of Pennsylvania, have invented certain Improvements in Railway-Ties, of which the following is a specification.

This invention relates to railway ties employing stone blocks for supporting the rails, 10 and its leading purpose is to produce such a tie with improved means for securing the rails to the blocks and fastening the blocks together.

The accompanying drawing represents a 15 transverse view of a track having rails supported by my improved tie.

As shown in the drawing, the tie consists of the natural or artificial stone blocks 1 connected by metal straps comprising the horizontal sections 2 resting on top of the blocks and supporting the rails 3, the hooks 2' with the rearwardly extending struts 2^a for engaging the webs 3' and the exterior flanges 3^a of the rails, the vertical sections 2^b joined by 25 the twisted sections 2^c to the horizontal sections 2 and extending diagonally from the inner upper corner of one block to the inner lower corner of the other, the horizontal sections 2^d lying beneath the blocks 1 and joined 30 to the vertical sections 2^b by the twists 2^e at the lower inner edges of the blocks, and the sections 2^f extending upwardly from the horizontal sections 2^d and bearing against the outer faces of the blocks. Bolts 4 pass 35 through the respective parts 1, 2, 2^d and the clips 5, which engage the inner flanges 3^b of the rail bases, and bolts 6 pass through the respective parts 1, 2' and 2^d, by which the parts are held together firmly and securely. 40 Ties thus formed are stable, strong, enduring and economical.

Having described my invention, I claim:—

1. In a railway tie, in combination with rails, blocks for supporting said rails, and straps each engaging the top of one block and the bottom of the other.
2. In a railway tie, in combination with rails, blocks for supporting said rails, straps each having integral parts of which one engages the top of one block and another engages the bottom of another block, and bolts

securing together the strap parts and the blocks engaged thereby.

3. In a railway tie, in combination with rails, blocks for supporting said rails, straps having parts disposed on top of the respective blocks and beneath the respective rails and parts disposed beneath the respective blocks, the parts of the respective straps being continuous and integral, and bolts for connecting the blocks with the respective strap parts.

4. In a railway tie, in combination with rails, blocks for supporting said rails, and straps respectively extending continuously from the bottom of each block to the top of the other, each strap having a part supporting a rail and provided with a hook for engaging the base thereof.

5. In a railway tie, in combination with rails, blocks for supporting said rails, and straps respectively provided with a part resting on top of a block and beneath a rail with a hook engaging the rail base, a part beneath the other block with an angular portion engaging the outer face thereof and a continuous connection between said parts.

6. In a railway tie, in combination with rails, blocks for supporting said rails, and straps connecting said blocks, each of said straps comprising a horizontal part supported on top of a block beneath a rail, a hook engaging the rail, a horizontal part supported against the bottom of the other block, and a vertical part integrally connected with the aforesaid parts and extending diagonally between them.

7. In a railway tie, a pair of blocks, a strap having a part secured to the top of one block and connected directly to the bottom of the other, said part having a hook with a reversely extending strut thereon, means for securing said strut to the corresponding block, and a rail supported by said part and engaged by said hook.

In testimony whereof I have hereunto set my name this second day of December, 1907, in the presence of the subscribing witnesses.

JOHN McGRANIGHAN.
